BLADE MAGAZINE

Joseph Muros, Cambridge, Mass., assignor to
Gillette Safety Razor Company, Boston, Mass.,
a corporation of Delaware

Original application December 24, 1937, Serial
No. 181,526, now Patent No. 2,132,798, dated
October 11, 1938. Divided and this applica-
tion March 16, 1938, Serial No. 196,259

6 Claims. (Cl. 206—16)

This invention relates to safety razors of the magazine type organized to receive as desired a sharp and unused blade from a pack supplied in a magazine or clip. In one aspect the invention 5 comprises a novel combination of safety razor and magazine in which the razor is organized to receive from the magazine a blade directly in shaving position whereupon the magazine may be removed, relinquishing the blade already positioned in the razor and carrying away those blades remaining in the pack. In another aspect the invention consists in a novel magazine or clip for safety razor blades adapted for use 10 in the combination described and for dispensing or delivering successive blades to the razor of the consumer.

The extreme thinness of safety razor blades and the fragile character of their shaving edges makes these blades difficult to handle and locate 20 ready for shaving in the razor without danger of cutting the user or of impairing the keen edge of the blade by contact with the razor or the blade packing. As herein shown the magazine of my invention is shaped to contain a plurality 25 of blades in a stack or pack, maintaining their cutting edges out of contact with all parts of the magazine and exposing only the body of the lowermost blade in the pack so that it may be directly presented in shaving position in the razor. The 30 razor, on its part, is designed to guide the magazine accurately into the proper blade delivering position, to locate it properly when once positioned and to hold it in place while the magazine is moved to release the blade so positioned.

To the ends above set forth an important feature of the invention consists in a magazine or clip of sheet metal, containing no moving parts and being capable of production at low cost so 35 that it may serve the purpose of a blade package 40 in distribution. Its construction is such, moreover, as to guard and protect the keen shaving edge of each blade contained therein up to the moment when it is deposited in shaving position in the razor.

These and other features of the invention will be best understood and appreciated from the following description of a preferred embodiment 45 thereof, selected for purposes of illustration and shown in the accompanying drawings, in which Fig. 1 is a view of the safety razor in front elevation;

Fig. 2 is a corresponding view in end elevation;

Fig. 3 is a corresponding view in rear elevation, 50 showing portions of the handle broken away;

Fig. 4 is a view in perspective of one form of blade adapted to be employed with the razor of my invention;

Figs. 5, 6, 7 and 8 are respectively an end view, 5 a view in front elevation, a sectional view on the line 7—7 of Fig. 6, and a plan view from beneath of one form of magazine in which the present invention is embodied;

Fig. 9 is a plan view and Fig. 10 a corresponding view in front elevation showing a portion 10 of the razor and the magazine partially withdrawn;

Fig. 11 is an end view on an enlarged scale 15 of the magazine in blade-delivering position in the razor;

Fig. 12 is a fragmentary view on the same scale in longitudinal section showing the magazine partly withdrawn;

Fig. 13 is an end view on a still larger scale 20 showing the location of a blade for shaving in the razor.

The razor shown in Figs. 1—3 is designed to take a narrow, straight, single-edged blade 50 of the type shown in Fig. 4 and is provided with a blade-seat for accurately positioning the blade and a guard for protecting the user. In these figures the razor is shown on about a one and one-half scale. It comprises a stationary guard member and a movable blade carrier. The guard member is preferably made of sheet metal and has a vertical stem portion 11, a forwardly and upwardly inclined body portion 12 and a downwardly inclined flange 13 which overhangs the blade when the razor is organized for shaving with a blade therein. 35

The blade carrier is also formed of sheet metal and has a body portion 14 hinged for swinging movement upon a horizontal pivot 15 mounted at the upper end of the stem portion 11. It has also a forward and downwardly inclined blade 40 seat 16 and a rearwardly and downwardly inclined guard flange 17 and is perforated for the sake of lightness. The blade seat 16 is provided with a longitudinal rib 18 from which projects a pair of spaced blade-engaging pins 19. As 45 shown in Fig. 4 the blade is provided with spaced apertures 51 to fit upon these pins which thus determine accurately the shaving position of the blade. A sheet metal spring 20 is secured to the stem 11 and tends always to swing the blade carrier upwardly toward the body portion 12 of the guard member. The guard member is provided with a slot through which extends a headed stud 21 which is fast in the blade carrier and by depressing this stud the blade carrier may be 50 55

swung downwardly and forwardly into blade receiving position as shown in Fig. 2. The blade seat 16 is provided near its outer corners with a pair of projecting guard lugs 22 which mask the corners of the blade and so protect the user from being cut or scratched by them. The blade seat is also provided at one end with a pair of spring fingers 23, shown on a large scale in Fig. 12, and adapted to engage one end of a blade placed upon the blade seat and to hold it frictionally in place thereon pressing yieldingly and longitudinally against the pins 19.

It will be understood that the blade holder may be swung into its place receiving position as shown in Fig. 2 by pressure upon the stud 21 and that a blade 50 may then be positioned upon the pins 19 by placing it on the blade seat and forcing it slightly toward the left as seen in Fig. 1, placing the spring fingers 23 under tension and bringing the blade apertures 51 into registration with the pins 19. When this has been done and pressure upon the stud 21 released, the blade holder immediately swings upwardly carrying the rear portion of the blade 50 beneath the flange 13 of the guard member. This flange 13 and the guard flange 17 of the blade carrier act as co-operating guard surfaces to determine a safe edge exposure for the blade.

A preferred embodiment of the blade magazine 30 or clip of my invention will now be described and then it will be explained how this may be utilized for supplying a single blade at a time to the razor already described. The magazine may be formed substantially or entirely of sheet metal. It is generally rectangular in form and square in cross-section, having a front wall 30 which terminates in a flat inturned flange 31. The magazine has also a top wall 32 and a rear wall 33 which is extended downwardly below the edge of the front wall 30 so that it provides a guide or positioning flange projecting below the body of the magazine. The rear wall is also provided with an inturned flange 34 corresponding to the flange 31 of the front wall and spaced therefrom so as to expose the body portion of the lowermost blade in the pack by a distance just equal to the width of the rib 18 on the blade seat of the razor. In effect the bottom of the magazine is slotted or apertured to the width of the space between the inner edges of the flat flanges 31 and 34. The rear wall 33 is also provided with an external rib 35 which is located slightly above the level of the flange 34. It is herein shown as a solid rib but may be formed as corrugation in the metal of the magazine. From the description thus far it will be seen that the magazine is adapted to contain a pack or stack of blades 50 arranged longitudinally one above another, the lowermost blade being supported by and exposed between the inturned flanges 31 and 34.

The inturned flanges 31 and 34 of the magazine are cut off somewhat within the left end of the magazine as shown in Fig. 8 and are provided at their right end with downturned ears or hooks 41 which act as stops to limit the movement of the magazine toward the left upon the blade seat of the razor. The flanges are cut off at their left ends to facilitate disengagement of the blade when the magazine is retracted, as will be presently explained, and to eliminate the danger of prying up the blade upon the blade seat by accidental tilting movement of the magazine at the end of its withdrawing movement. At its right end the magazine is provided with a long end wall or lug 37 which extends from the top 32

of the magazine downwardly beyond the end of the lowermost blade supported upon the flanges 31, 34. The magazine is correspondingly provided at its left end with a shorter end wall or lug 36 which is of such length as just to clear the lowermost blade in the pack and so permit that blade to be moved endwise beneath the lug, or to permit the blade to remain at rest while the magazine is moved endwise to relinquish the blade. The magazine is also provided internally upon its front wall 30 with a pair of spaced vertical blade-guiding ribs 39 which are arranged to engage the sharp edges of the blades in the stack only at their extreme outer corners in such manner that the cutting edge as a whole is prevented from coming in dulling contact with the magazine. The guide ribs 39 also terminate in position to clear the lowermost blade in the pack and so leave its cutting edge entirely free for the retracting movement of the magazine. The magazine is also provided with a curved-leaf spring 40 located below its top wall and tending at all times yieldingly to press the blade pack downwardly and maintain the lowermost blade in contact with the flanges 31 and 34.

It will be understood that the magazine is loaded with a stack or pack of perhaps ten loose unwrapped blades. These are enclosed by the walls and top of the magazine except for a central longitudinal zone in the undersurface of the 30 lowermost blade in the pack.

In using the magazine above discussed to supply blades to the razor of Figs. 1-3, the stud 21 is depressed to swing the blade carrier forwardly into blade-receiving position and the magazine is placed upon the blade seat with the wide flange formed by its rear wall 33 in contact with the rear face of the body portion 14 of the blade carrier, as best shown in Fig. 11. The magazine may be placed in this position and then pushed toward the left as seen in Fig. 1 being guided in this movement by its downwardly extending flange. The stud 21 is now released and the blade carrier will be moved rearwardly with the magazine until the rear wall of the magazine encounters the forward edge of the flange 13 of the guard as shown in Fig. 11. The flange 13 engages the magazine just above its external rib 35 and, therefore, tends not only to push it forwardly upon the blade seat but to hold it down against removal. The movement of the magazine toward the left is continued until arrested by engagement of the stops 41 against the right hand edge of the blade seat. This movement of the magazine is gauged by the stops so that the lowermost blade 50 in the magazine is forced at its end against the spring fingers 23 displacing them outwardly and itself coming into registration with the pins 19. It will be noted that in this movement the spaced flanges 31 and 34 of the magazine engage between them the rib 18 of the blade seat, all as shown in Fig. 11.

When the lowermost blade in the magazine has been positioned as above explained, it remains only for the user to move the magazine bodily 65 toward the right, as suggested in Figs. 9 and 10, leaving the blade positioned upon the blade seat. In this movement the magazine is again guided by the contact of its downwardly extending flange with the body portion 14 of the blade carrier and 70 by the engagement of its flanges 31 and 34 with the rib 18. During this movement it is also held against displacement by the engagement of the flange 13 of the guard with its external rib 35. Movement of the magazine toward the right is 75

continued until the magazine is entirely withdrawn from the blade, the latter passing under the wall 28 and being left in shaving position without any damaging contact with its shaving edge. Pressure of the spring 40 at once replaces the delivered blade in the magazine by the second blade in the pack when the magazine has been drawn clear of the guard member of the razor. When the magazine has been moved to the right sufficiently to clear the razor the spring 28 is effective to restore the blade carrier and the blade 50 to shaving position beneath the flange 13 of the guard as shown in Fig. 13 and the razor is ready for shaving.

15 After shaving, the used blade may be removed from its seat either by prying up one end of the blade sufficiently to disengage one of the pins 19, or by smartly shaking the opened razor so that the frictional engagement of the fingers 23 is overcome to the extent of releasing the blade.

20 The present application is a division of my prior application Serial Number 181,526, filed December 24, 1937, now Patent No. 2,132,798, granted October 11, 1938, wherein I have claimed 25 the novel combination of safety razor and magazine herein disclosed, this application being limited to the magazine alone.

Having thus disclosed my invention and described a preferred embodiment thereof for purposes of illustration but not by way of limitation, I claim as new and desire to secure by Letters Patent:

30 1. A blade magazine having side walls each provided with an inturned blade-supporting flange, the said flanges being hooked at one end and cut back at the other within the end of the magazine, a blade-retaining lug located between the hooked ends of the flanges, and a shorter blade-retaining lug being located beyond the cut 35 back ends of the flanges.

35 2. A blade magazine comprising an enclosure rectangular in cross section and having flat, in-turned bottom flanges spaced from each other, a plurality of individual blades contained within the enclosure, the lowermost blade being perforated and resting upon said spaced flanges with its 40 perforations exposed between their edges to receive blade-engaging elements of a razor, and a positioning flange on the magazine extending be-

low said spaced flanges to engage the razor and register its blade-receiving face with respect to said lowermost blade.

3. A blade magazine comprising an enclosure 5 rectangular in cross section and having spaced bottom flanges, a plurality of individual blades contained within said enclosure, the lowermost blade being perforated and retained by said spaced flanges with its perforations exposed to receive blade-engaging elements of a razor, the magazine having also a positioning flange extending below said spaced flanges to engage the razor and register it with respect to said lowermost blade and a laterally projecting rib by which it may be held upon the razor.

4. A blade magazine comprising an elongated enclosure having spaced bottom flanges, a plurality of individual blades contained within said enclosure, the lowermost blade being perforated and retained by said spaced flanges with its perforations exposed, the rear wall of the enclosure being extended downwardly below said bottom flanges to provide a positioning device to engage the razor and register it with respect to said lowermost blade, an exterior rib adjacent to said 25 positioning device, and end lugs of unequal length forming a part of the enclosure.

5. A blade magazine comprising an elongated enclosure having spaced bottom flanges, a plurality of individual blades contained within said 30 enclosure, the lowermost blade being perforated and retained by said spaced flanges with its perforations exposed to receive blade-engaging elements of a razor, the said spaced flanges having stops at one end and being cut away at the other 35 end short of the end of the enclosure.

6. A blade magazine comprising an elongated enclosure having flat inturned spaced bottom flanges, a plurality of individual blades contained within said enclosure the lowermost blade being 40 perforated and retained by said spaced flanges with its perforations exposed to receive blade-engaging elements of a razor and the magazine being provided with a positioning flange to engage the razor and register its blade-receiving face 45 with respect to said lowermost blade and having also internal ribs for holding the sharp edges of the blades from contact with the enclosure.

JOSEPH MUROS.
